[57] CLAIM

The ornamental design for a gas fired hot water pressure cleaning apparatus, as shown and described.

DESCRIPTION

FIG. 1 is a perspective view of a gas fired hot water pressure cleaning apparatus showing my new design;

FIG. 2 is a top plan view thereof;

FIG. 3 is an end elevational view thereof taken from the left side of FIG. 2; and

FIG. 4 is a side elevational view thereof, the side opposite being a mirror image.

FIG. 2FIG. 3FIG. 4
